Patented Nov. 18, 1919.

UNITED STATES PATENT OFFICE.

WILLIAM G. HAYNES, OF COFFEYVILLE, KANSAS.

PLUG FOUNDATION FOR WELLS.

1,322,436.

Specification of Letters Patent. Patented Nov. 18, 1919.

Application filed February 10, 1919. Serial No. 276,000.

To all whom it may concern:

Be it known that I, WILLIAM G. HAYNES, a citizen of the United States, residing at Coffeyville, in the county of Montgomery and State of Kansas, have invented certain new and useful Improvements in Plug Foundations for Wells; and I hereby declare that the following is a full, clear, and exact description thereof, reference being had to the accompanying drawings, which form part of this specification.

This invention is a novel plug foundation or support to be used in oil wells, and the like, when it is desired to insert a plug to seal up such well, or a portion of the well, as sometimes becomes desirable.

The object of this invention is to provide a simple device which can be inserted in the well and lowered to the desired point and then readily expanded and secured therein, so that it will form a substantial foundation for the sealing plug; which can be subsequently seated thereon.

The device can be used as a foundation or support upon which plugs can be set at any given depth or place in an oil or gas well. Sometimes when a well is drilled a sand strata is struck which while producing oil or gas does not do so in the desired quantity; and then drilling is continued and after drilling the well deeper salt water is encountered. If this salt water is allowed to rise into the oil or gas producing sand, and remain there any length of time, it will eventually ruin the sand; so it is necessary to plug the well above this salt water in order to save the values in the sand above it. The method commonly used at present is to fill in the hole with stone, sand, cement and the like, for some distance above the salt water to form a base upon which to drive a plug, usually of the expandable type, for if it is attempted to drive such a plug in the soft strata in which the water is found the plug will be ineffective and let the water pass. The said common method of forming a foundation for the plug is also wasteful in materials and costly as much time is lost waiting for the cement to set, for which time the workmen have to be paid.

My novel plug foundation or support can be lowered to any depth desired in such a well, tripped at that depth, and firmly secured in position in a few minutes; and it forms a substantial and secure support for the plug in the well; and any desired kind

of expandable plug can be at once lowered onto said support and driven home to seal the well. The more weight and pressure exerted downwardly upon the support and the harder the plug is driven, the more securely the support is caused to hold in position.

I will describe one practical embodiment of the invention as illustrated in the accompanying drawings to enable others to adapt and use the same, but do not consider the invention restricted to the particular form or features of construction shown, except as the same may be recited in the more specific claim. I refer to the claim for summaries of the essentials of the invention and novel features of construction and novel combinations of parts for which protection is desired.

In said drawings:

Figure 1 is a perspective view of the plug support ready for insertion into a well.

Fig. 2 is a reduced horizontal section therethrough on the line 2—2, Fig. 3.

Fig. 3 is an enlarged vertical section thereof on line 3—3, Fig. 2.

Fig. 4 conventionally illustrates the manner of securing the plug support in a well.

As shown the plug support or foundation device has a base member 1 which may be of any suitable form and horizontal transverse cross section, but of such size that it will enter freely within the bore of the well in which the support is to be secured.

This base member 1 is provided with a central vertical opening 1^a for the reception of a wedge pin 3; and it is also provided in its sides with a plurality of radially disposed slots 1^b in which are mounted sliding dogs or bars 2. The bars 2 are provided on their outer ends with preferably enlarged heads 2^a, which are also transversely toothed or serrated as shown, so that they will readily bite the walls of the well when forced thereagainst. The inner end of each sliding bar 2 is also preferably beveled as shown at 2^b, and engages an opposed correspondingly beveled surface 3^b of the wedge-pin 3.

The wedge-pin 3 preferably corresponds in cross section with the opening 1^a in the base member, and has a series of longitudinally disposed slots or grooves 3^a in its sides, one for each slide bar 2; and the wedge surfaces 3^b are preferably formed in the bottoms of the grooves 3^a in the sides of the wedge-pin. Said grooves preferably

correspond in width to the thickness of the slide bars 2 and assist in guiding the same, and prevent their being deflected laterally by the pressure of the wedge surfaces thereby against.

When the wedge-pin is entirely raised (as indicated in full lines in Figs. 1 and 3) the slide bars are in their innermost positions, and their heads nearest the sides of the base 10 1; the foundation or support being then contracted and ready for insertion into a well.

When the support is to be placed in a well it should be contracted, as indicated in Figs. 1 and 3, and when so contracted a 15 weak confining wire or cord 7 may be placed around the base and heads, (as indicated in Figs. 1, 2 and 3); this cord being adapted to be easily ruptured upon the forcible descent of the pin 3 after the plug support 20 has been lowered to the desired position in the well as hereinafter explained.

The plug support may be carried while in contracted condition by any suitable means. As shown a bail 8 of wire or cord 25 has its ends attached to the base at opposite sides of the wedge-pin as indicated in the drawings, or in other suitable way, and extends up over the top of the wedge-pin, which is shown as provided with a head 3°, 30 having perforations 3^a, for the passage of the bail 8; but the bail 8 may be arranged in other suitable manner.

When the support is to be lowered into a well, a cord or rope 4 is engaged with the bail 8 above the wedge-pin, as indicated in 35 Figs. 1-3, so as to suspend the base and connected parts, leaving the wedge-pin raised and the slide bars (or dogs) retracted.

The support can then be lowered into 40 the well to the desired depth. When the desired depth is reached, a weight 5, (which may be of cast iron with a hole in its center for the double rope 4 to run through) is slipped on to the double rope 4 and re- 45 leased at the top of the well; this weight slides down the rope by gravity and strikes the top of pin 3 driving said wedge pin down in the base, which is suspended by the rope; and when the pin is thus driven

into the base it forces the slide bars or dogs 50 2 outwardly and against the side walls of the well and securely wedges the slide bars radially in the well, and the bars support the base and pin and hold the base stationary and firmly in position; and the more 55 weight or pressure put on the pin, the more tightly the bars are caused to bite the wall as the wedge surfaces on the pin the more forcibly push out the bars or dogs.

The rope 4 can then be easily removed 60 by releasing one end at the top and drawing it out by the other end. Any suitable expansible plug or packing (not shown) can then be lowered onto the support and be driven firmly in place. The more weight 65 and force exerted upon the support in driving the plug or packing thereon the more tightly will it bite the wall.

The plug supports are to be made of various sizes to suit different wells; they are not 70 unwieldy nor very heavy; and it will be easy for drillers to carry one or more of these plug supports in their cars ready for use at a moment's notice.

What I claim is:

In a plug support or foundation for the purpose specified; a base member; radially movable members mounted on said base member, a vertically movable wedge member mounted on the base member and adapted 80 to force the radially movable members outward when the wedge member is driven downward; a carrier connected with the base and adapted to be connected to a rope whereby the foundation may be suspended 85 in a well at any desired depth, means for yieldingly holding the movable members retracted and the wedge member raised while the base member is being lowered into the well and suspended in position therein, 90 and means for driving the wedge member after the base member is lowered to the desired position and while it is suspended by the carrier in the well.

In testimony that I claim the foregoing 95 as my own, I affix my signature.

WILLIAM G. HAYNES.
